COMBINED FLOWER POT AND BASE

Gregory D. Fox and Vincent J. Fox, both of 910 N.
Huntington St., San Fernando, Calif. 91340

Filed Dec. 11, 1972, Ser. No. 314,126

Term of patent 14 years

Int. Cl. D11—02

U.S. Cl. D35—3 A

FIG. 1 is an exploded side elevational view of a combined flower pot and base embodying our new design;

FIG. 2 is a top plan view of the flower pot illustrated in FIG. 1;

FIG. 3 is a top plan view of the base illustrated in FIG. 1;

FIG. 4 is a side elevational view showing the flower pot illustrated in FIG. 1 resting in its base; and

FIG. 5 is a side elevational view of a combined flower pot and base illustrating a second embodiment of our design.

We claim:

The ornamental design for a combined flower pot and base, as shown and described.
